UNITED STATES PATENT OFFICE.

ARTHUR W. TOWER, OF RIDGE HILL, MASSACHUSETTS.

MACHINE FOR GAGING TOE-CAPS AND MARKING VAMPS.

SPECIFICATION forming part of Letters Patent No. 372,644, dated November 1, 1887.

Application filed May 9, 1887. Serial No. 237,562. (No model.)

To all whom it may concern:

Be it known that I, ARTHUR W. TOWER, of Ridge Hill, county of Plymouth, and State of Massachusetts, have invented an Improvement 5 in Machines for Gaging Toe-Caps and for Marking Vamps, of which the following description, in connection with the accompanying drawings, is a specification, like letters on the drawings representing like parts.

This invention has for its object to construct a machine for gaging toe-caps, to facilitate fastening the same to the vamps of boots and shoes, and also for marking the vamps to facilitate the accurate application of the top pieces to 15 the vamps.

In accordance with this invention the vamp, placed or held upon the bed-plate, is acted upon by a suitable guide or gage having a curved face or edge, against which is placed 20 or pressed one edge of the toe-cap which is to be pasted to the toe part of the vamp. Suitable adjusting devices are provided for the said guide or gage, to compensate for the different sizes of vamps.

The machine to be herein described contains 25 a marking-tool and suitable centering devices, by which to center and then mark the vamp at a point at the center of the instep portion, such mark or indication serving as a guide for 30 the front seam or opening of the top piece or quarter.

Figure 1 shows in plan view a machine for gaging toe-caps and for marking vamps embodying this invention; Fig. 2, a vertical section of Fig. 1, taken on the dotted line $x-x$; Fig. 3, a sectional detail of the machine taken 35 on the dotted line $y-y$; Fig. 4, a sectional detail of the machine taken on the dotted line $z-z$, and Figs. 5, 6, 7, 8 details to be referred 40 to.

The main frame-work A of the machine comprises a suitable bed-plate and supporting legs or standards therefor.

The vamp, (shown by dotted lines,) having 45 been laid upon the bed-plate, is held in fixed position thereon and properly centered by a centering device, herein shown as consisting of two forms, ff' , placed side by side, but made movable toward and from each other, said 50 forms being shaped exteriorly to conform to the shape of the instep portion of the vamp, or that part to which the top pieces are at-

tached. The forms ff' are each placed upon pins 6 6, (see Fig. 5,) secured to two laterally-movable plates, $f^2 f^3$, fitted in the bed-plate. 55

Each plate $f^2 f^3$ is provided with a pin or stud, as 7, said pins or studs entering slots cut in a plate, f^4 , secured to a shaft, f^5 , having its bearings in the bed-plate between two slotted plates $f^2 f^3$, so that as the said shaft is rotated 60 the plates $f^2 f^3$ will be moved toward and from each other. The plate f^4 is held down firmly upon the form by drawing the shaft f^5 down through the bed-plate by a spring, 8. The vamp being placed in position, the shaft f^5 is 65 rotated sufficiently to cause the forms ff' to snugly fit the opening in the vamp at the instep portion, after which the marking-tool, herein shown as having a push-point, p , moving in the guide-frame p' , fixed to the bed-plate, is 70 depressed, so that its point indents the face of the vamp at the center line to thereby mark the place of the front seam or opening of the top piece. The push-point p is normally held in elevated position by a suitable spring, p' . 75 (See Fig. 2.)

The vamp toe cap gage or guide is herein shown as an open frame composed of side bars, $a a'$, hinged to a projection, a'' , rising from a block or plate, d , dovetailed into the bed-plate 80 and made movable longitudinally therein, the said bars $a a'$ being joined together at their opposite ends by a strip or bar of material, a^3 , having a curved outer edge (see Fig. 1) to act as a gage for the toe-cap. The frame referred to has a cross-bar, b , against the under side of which bears the outer or free end of a spring, b' , acting to normally keep the gage in elevated position. The operating-lever c , pivoted to the upper side of the block d , and 85 resting at its free end on the cross-bar b , is joined by a connecting rod or link, t , to a treadle, t' , so that as the treadle is depressed the operating-lever c will strike the cross-bar and cause the gage to descend and bear upon the 90 vamp placed upon the bed-plate, as shown by dotted lines. The block or plate d has at its under side a projection, d' , screw-threaded to receive the threaded end of a rod, d^2 , having its bearing in the frame-work of the machine, 95 and provided with a hand-wheel, d^3 , by which it may be rotated, to thereby move the block d longitudinally.

A sliding plate, e , dovetailed in the bed-

plate, has two series of graduations, 23, one of which, as 3, co-operates with a fixed point, 4, to adjust for vamps of different length, which are cut to fit lasts of different styles, it being understood that some styles of lasts are longer than others, although of the same size. The other series of graduations, 2, co-operate with the gage for a^3 , to adjust for the different sizes regularly. By making a single adjusting device of this kind the said screw 5 is turned until the required position is secured for a last of the style to be used, the different sizes being gaged by the device a^3 . When the gage is held depressed, the toe-cap will be applied to the vamp with its edge against the gage-bar a^3 , as above described.

It is obvious that, if desired, either the toe-cap-actuating device or the marking device may be employed singly.

20 The forms f^f' are shown as detachable, so that forms of different configuration may be substituted for vamps of different styles.

I do not desire to limit my invention to the precise construction of devices herein shown, 25 as they may be materially modified, and yet the result above specified may be accomplished.

I claim—

1. In a machine for gaging toe-caps, the longitudinally-recessed bed-plate to support the 30 vamp, combined with the gage a^3 , having a curved face against which the edge of the toe-cap is held while being fastened, substantially as described.

2. In a machine for gaging toe-caps, the longitudinally-recessed bed-plate and adjustable 35 spring-clamp and centering devices for the vamp, combined with the movable gage and

adjusting devices for it, substantially as described.

3. In a machine for gaging toe-caps, the longitudinally-recessed bed-plate and means for holding the vamp upon the plate, combined with the movable gage and adjusting devices for the gage, consisting of the screw-actuated sliding plate e , having two series of graduations, substantially as and for the purposes specified. 40

4. The bed-plate and means for holding the vamp upon the bed-plate, combined with the pivoted gage, the block d , operating lever c , 45 and screw-rod, substantially as described.

5. The bed-plate and adjustable centering device for holding the vamp in position upon the bed-plate, combined with the marking-tool p , for marking, as described, the center 55 line of the vamp, substantially as and for the purpose specified.

6. The bed plate and laterally-movable detachable forms f^f' , combined with the plates $f^2 f^3$, the slotted plate f^4 , shaft f^5 , and the marking tool, as p , substantially as described. 60

7. The bed-plate and forms f^f' , movable toward and from each other, combined with means for moving the forms and a spring-controlled marking tool, substantially as described. 65

In testimony whereof I have signed my name to this specification in the presence of two subscribing witnesses.

ARTHUR W. TOWER.
